(57) **CLAIM**

The ornamental design for a hangtag, as shown and described.

DESCRIPTION

FIG. 1 presents a perspective view of a handtag for a tool product embodying the new design;

FIG. 2 is a front elevation view of the hangtag of FIG. 1;
FIG. 3 is a side elevation view of FIG. 1, the other side not
shown being a mirror image of the side shown in this view;
FIG. 4 is a top view of the hangtag of FIG. 1; and,
FIG. 5 is a bottom view of the hangtag of FIG. 1.

The hangtag is for holding a ratchet driver. The ratchet driver
in not shown or claimed.
